INVENTOR
OLGA L. CHARTERS
BY *W. Harrison*
ATTORNEY.

UNITED STATES PATENT OFFICE.

OLGA L. CHARTERS, OF LOS ANGELES, CALIFORNIA.

COLLAPSIBLE BOX.

Application filed September 3, 1924. Serial No. 735,720.

To all whom it may concern:

Be it known that I, OLGA L. CHARTERS, a citizen of the United States, and resident of Los Angeles, in the county of Los Angeles and State of California, have invented certain new and useful Improvements in Collapsible Boxes, of which the following is a specification.

This invention relates to receptacles suitable for use by travellers who may desire that their baggage, when no articles of apparel are to be contained therein, shall occupy a minimum amount of space. The invention has particular reference to such receptacles designed to contain, when not collapsed, such articles as women's hats.

A particular object of the invention is to provide a box which, when open or set up, may contain one or more hats, but which, when not to be used as a container for anything, may be collapsed so as to occupy little space in a trunk or on a shelf in a closet, or elsewhere.

Of the accompanying drawings which illustrate a preferred embodiment of my invention,

Figure 1 is a perspective view of the box in set up condition, ready for transportation or storage with hats or other articles contained therein.

Fig. 2 illustrates the set up box with the cover or lid open.

Figure 3 illustrates the box in partly collapsed condition, and

Figure 4 illustrates the box in completely collapsed or folded condition, but inverted to show the bottom.

Similar reference characters designate similar parts or features in all of the views.

The main or receptacle member of the box comprises a bottom 12, a front wall 13, side walls 14, and a compound or double rear wall consisting of two inner substantially triangular sections 15 and an outer section 16 which latter connects the bottom 12 with the cover or lid member 17. Said member has flanges 18 and carries a catch 19 to be engaged with a lock member 20 (Fig. 3) carried by the front wall 13, when the box is set up and closed.

Preferably the bottom 12 is of double-thick material and has small knobs 21 (Fig. 4) which act as feet for the box when in use. The several portions of the box are made of as many pieces of suitable stiff ma-

terial as may be desired, such pieces being secured together in any preferred manner.

To enable the box to be folded or collapsed, different members thereof are creased or so connected as to provide hinges. For convenience of description such creases or connections will be hereinafter referred to as fold lines.

The side walls 14 have diagonal fold lines *a* and are foldable on lines *b* relatively to the bottom 12, on lines *c* relatively to the front wall 13, and on lines *d* relatively to the triangular sections 15. Said sections 15 are connected to the section 16 on fold lines *e* (Fig. 3). The section 16 is foldably connected with the bottom 12 on line *f* and with the cover 17 on line *g* and is itself foldable on an intermediate line *h*. The front wall 13 is foldable on line *i* toward the bottom 12. It will now be understood that folding occurs at all places where letters are employed instead of numerals.

Pivotedly carried by each triangular section 15, in about the location illustrated, is a clip or latch 22.

Secured to one of the side walls 14 is one end of a long strap 23 and secured to the opposite side wall is a short strap 24 having a buckle 25, the cover 17 having strap-engaging or strap-guiding strips 26 (Fig. 1).

Secured to the inner surface of the cover 17 at the central portion thereof are two flaps 27 (Figs. 2 and 3), preferably consisting of an oval piece of suitable fabric secured at its mid-length to the cover and having its margin 28 stiffened by wire or pasteboard. The purpose of said flaps will be described hereinafter.

When the box is to be converted from collapsed condition as illustrated by Figure 4 to a set up or open condition as illustrated by Figure 2, it is first laid open as shown by Figure 3. Then the front wall 13 may be swung up and doing this effects a pull upon the side walls to swing them up toward upright position. And at the same time, owing to the connections of the several sections or members, the section 16 is partly lifted. The sides may then be readily manipulated to upright positions and the section 16 pushed up far enough to permit the two clips 22 to be swung over or around so as to lap over the edges of the section 16 as shown by Figure 2. This swinging of the clips puts and holds the box in condition to

receive whatever is to be placed therein, because it holds the inner and outer sections of the rear wall in upright condition. The open space between the triangular sections 5 15 enables an article such as a hat to be carefully placed in the box by means of one hand extending under the hat, if desired, and of course said space enables an article such as a hat to be carefully lifted out of 10 the box with more care than if the rear wall had no such space.

After closing the cover or lid, the strap 23 is passed over it and slipped through the guides 26 and secured by the buckle 25. 15 The function of this strap 23 is two-fold, viz: it serves as a handle for carrying the box and its contents, and it holds the side walls from springing in. This last is due to the fact that the buckled straps 23, 24, are 20 connected to the side walls and pass up around the flanged edges of the cover which, in practice, is stiff enough to resist collapsing strain when the box is in the condition shown by Figure 1 and is being carried.

25 To convert the box from the set up condition shown by Figure 1 to the flat collapsed condition shown by Figure 4, it is only necessary to un-buckle the strap 23 and slip it out from the guides 26, then lay the 30 cover back or even without laying the cover back swing the clips 22 out of engagement with the section 16, and then the box will almost automatically assume the flat folded condition shown by Figure 4.

35 It will now be understood that when the box is collapsed, the front wall and the side walls are folded in and, with their fold lines *a* and *e*, are confined between the bottom section 12 and the cover or lid 17, the flanges 40 18 of the latter extending over and protecting from wear all of the folds at the lines *b*, *c* and *i*. Therefore, since the bottom section 12 and the cover 17, 18, are readily made of strong and durable material, reinforced or 45 double-thick if desired, the box as a whole will withstand very rough usage such as, for instance, when folded flat and packed with other articles in a trunk which latter is then subjected to extended and varied 50 travels.

The flaps 27, carried by the central portion of the cover or lid, provide means whereby the box may safely contain two hats without interference one with the other. When so employed, one hat will be placed 55 on the bottom of the set up box and the other suspended, inverted, from the flaps 27, by means of hat pins, or one pin, passed through the flaps and through the portion of the inverted hat which usually receives a 60 pin or pins when the hat is worn. And of course if the box is to contain but one hat, that one may be secured to the flaps 27 in the manner just referred to, and be thereby held against lateral shifting within the box. 65

The location of said flaps as described ensures retention of such hat in a position where its brim will not be liable to be injured by contact with the side walls of the box.

Having now described my invention, I claim:—

1. A collapsible box having one of its walls formed to provide an open space when the box is set up to receptacle condition, said 75 box having a cover and a foldable section connecting it with the bottom of the box, said foldable section being formed to extend over said open space when the box is set up and closed. 80

2. A collapsible box comprising a bottom having wall sections and a cover all of which are permanently connected, a piece of flexible material being secured at its mid-length to the central portion of the inner surface 85 of the cover.

3. A collapsible box comprising a bottom section, a front wall section, side-wall sections having diagonal crease lines, inner and outer rear-wall sections, and a cover section, 90 all of said sections being connected and foldable relatively to each other, the outer rear-wall section being transversely foldable to enable it to be doubled, and clips attached to the inner rear wall and movable to position to overlap the outer rear wall to hold the box in set up condition. 95

In testimony whereof I have affixed my signature.

OLGA L. CHARTERS.
